FIG. 1.

FIG. 2.

FIG. 3.

FIG. 4.

FIG. 5.

FIG. 6.

FIG. 7.

FIG. 8.

FIGURE 1 is a front elevational view of the medical liquid container showing a first embodiment of my new design, the undisclosed rear being a mirror image of the front;

FIGURE 2 is a right side elevational view of the first embodiment, the undisclosed left side being a mirror image of the right side;

FIGURE 3 is a bottom plan view of the first embodiment;

FIGURE 4 is a top plan view of the first embodiment;

FIGURE 5 is a front elevational view of a second embodiment of my design, similar to the first embodiment but with a wider body making the container appear less elongated than the FIG. 1 embodiment; the undisclosed rear being a mirror image of the front;

FIGURE 6 is a right side elevational view of the second embodiment, the undisclosed left side being a mirror image of the right side;

FIGURE 7 is a bottom plan view of the second embodiment; and

FIGURE 8 is a top plan view of the second embodiment.

I claim:

The ornamental design for a medical liquid container, as shown and described.
